US0D1001114S

(12) **United States Design Patent** (10) **Patent No.:** **US D1,001,114 S**
Kim (45) **Date of Patent:** ** *Oct. 10, 2023

(54) **CASE FOR ELECTRONIC COMMUNICATIONS DEVICE**

(71) Applicant: **SPIGEN KOREA CO., LTD.**, Seoul (KR)

(72) Inventor: **Ji Hyun Kim**, Seoul (KR)

(73) Assignee: **SPIGEN KOREA CO., LTD.**, Seoul (KR)

(*) Notice: This patent is subject to a terminal disclaimer.

(**) Term: **15 Years**

(21) Appl. No.: **29/652,575**

(22) Filed: **Sep. 24, 2020**

(51) **LOC (14) Cl.** **14-03**

(52) **U.S. Cl.**

USPC **D14/250**

(57) **CLAIM**

The ornamental design for a case for electronic communications device, as shown and described.

DESCRIPTION

FIG. 1 is a front, right-side, and top perspective view of a case for electronic communications device showing my new design;

FIG. 2 is a rear, left-side, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
